UNITED STATES PATENT OFFICE.

REINHARD MANNESMANN, OF REMSCHEID, GERMANY.

MANUFACTURE OF SEAMLESS TUBES.

SPECIFICATION forming part of Letters Patent No. 361,956, dated April 26, 1887.

Application filed March 28, 1887. Serial No. 232,791. (Model.) Patented in England January 27, 1885, No. 1,167; in France January 27, 1885, No. 168,433; in Germany January 27, 1885, No. 34,617; in Belgium January 27, 1885, No. 67,667; in Italy January 26, 1886, No. 7,925; in Luxembourg June 20, 1886, No. 704; in Spain August 21, 1886, No. 9,537, and in Austria-Hungary September 18, 1886.

To all whom it may concern:

Be it known that I, REINHARD MANNESMANN, of Remscheid, Germany, have invented certain Improvements in Apparatus for Manufacturing Seamless Metallic Tubing, of which the following is a specification.

This invention is a modification of the invention which I have shown and described in another pending application for a patent, relating to the manufacture of seamless tubing from solid metallic blanks by the employment of diagonally-acting rolls, the working-faces of which converge, and between which there is placed a slender rod for holding back the solid central portion of the blank during its endwise progress between the rolls and consequent transformation into a tube.

The present invention is especially applicable to the manufacture of seamless tubing from solid metallic blanks composed of metals or alloys which are so soft and ductile as not to require to be heated to a high temperature to fit them for subjection to the action of the rolls.

The invention consists in the combination, with suitably-adjusted diagonally-acting rolls having convergent working-faces, of a cone-pointed mandrel, which is arranged to project a prescribed distance into the space between the working-faces of the rolls, and hence to penetrate the center of the forwardly-progressing blank and to thereafter serve as an anvil or former, over the surface of which the metal composing the blank is forced by the reducing and stretching action of the diagonally-acting convergent rolls, and is thus transformed into a tube, the interior diameter of which is determined by the diameter of the base of the cone, and the exterior diameter of which is determined by the width of the narrowest part of the space between the working-faces of the rolls. The diagonally-acting rolls are feeding-rolls, inasmuch as they perform the function of feeding the blank forward against and over the surface of the conical or conoidal mandrel, and it will be seen that the apparatus may be employed for reducing the thickness of the shell of a tube already formed by enlarging its interior diameter.

As diagonal rolling-machines are well known, they need not be herein described in detail. The accompanying drawings therefore are simply designed to show a pair of diagonally-acting rolls having convergent working-faces and arranged on either side of a cone-pointed mandrel, the shaft of which is stepped or journaled in a standard or some other stationary part of the machine.

The drawings are as follows: Figure 1 is a top view of two diagonally-acting rolls arranged, respectively, on opposite sides of a horizontal cone-pointed mandrel, showing in central longitudinal section a blank which has so far progressed in its passage between the rolls that the tubular formation has been initiated at its forward end. Figs. 2 and 3 illustrate successive intermediate stages in the operation of transforming a solid blank into a tube, and Fig. 4 illustrates the conclusion of the operation.

For the sake of clearness in illustration and description, it is assumed that in the machine the operative parts of which are illustrated in the drawings two conical diagonal rolls are employed, and that the vertical planes of the axes of these rolls are parallel, but incline in opposite directions from the horizontal plane of the mandrel, which is interposed between the rolls. It will be understood, however, that three, or even four, rolls may be employed in connection with the mandrel. When more than two rolls are employed they serve to centralize the blank. When only two rolls are employed the centralization of the blank is effected by means of suitable guides. As, however, the employment of guides in combination with two diagonal rolls is well known, it is deemed unnecessary to herein show or describe them in detail.

The operative parts illustrated in the drawings consist of the conical rolls A a, which are respectively arranged on either side of a conical mandrel, B, which projects into the narrower end of the space between the working-faces of the rolls to such an extent as to cause its small end b to penetrate into the central portion of the solid blank C after the blank has been engaged by the rolls and has commenced to move

forward. The mandrel-shaft B' is stepped or journaled in the standard D or in some other stationary part of the machine.

In some cases it may be desirable to permit 5 the mandrel to be rotated by the friction upon its surface of the rotating blank. In other cases it may be preferred to hold the mandrel rigidly, so that it cannot revolve.

As the blank continues its progress between 10 the working-faces of the rolls the metal is forced forward over the mandrel, as shown in Fig. 2, and acquires the form of the hollow cylinder C', (shown in Fig. 3,) in which the rear end, C', of the blank is represented as having been carried forward nearly to the pointed end b of the mandrel.

Fig. 4 represents the conclusion of the tube-forming operation, after which the shaft may be disengaged from the socket d, in which it is 20 stepped or journaled, and the finished tube then slipped off the shaft.

It will of course be understood that instead 25 of the conical rolls shown in the drawings, rolls of other forms or kinds may be employed; and it will also be understood that the working-faces of the rolls may be made to converge more or less abruptly, as may be found necessary in practice in operating upon different metals. The working-faces of the rolls may 30 also, if required, be provided with spiral ribs or corrugations, for the purpose of enabling them to take a more effective hold upon the metal at the surface of the blank against which they impinge.

35 The mandrel may be of any suitable form in cross-section, and is preferably made in the form of a movable or detachable head seated in the end of a long bar of smaller diameter than the inner diameter of the tubular product. The mandrel may also be made hollow, 40 and cooled by means of an injected cooling fluid; but for the manufacture of tubes from soft metals it is preferred to use solid mandrels,

By the action of the conical rolls arranged with their larger ends nearer together than 45 their smaller ends, a progressively-increasing twist is imparted to the shell of the tubular formation while the shell is being progressively reduced in thickness by being compressed upon the surface of the conical mandrel. 50

What is claimed as the invention is—

1. The herein-described improvement in the art of forming a solid metallic blank into a tube of prescribed diameter and thickness of shell, in which, by the impingement upon the blank of diagonally-acting rolls having convergent working-faces, the blank is reduced in diameter and the metal thereof is forced against the small end and over the surface of 60 a conical mandrel, which acts as an anvil or former, upon the surface or upon some part of the surface of which the shell of the tube in process of formation is compressed by the rolls and its thickness thereby determined. 65

2. In diagonal-rolling machines, the combination, as herein set forth, of diagonally-acting feeding rolls with a conical mandrel projecting a prescribed distance into the space between the working-faces of the rolls and 70 serving as an anvil or former, against and over the surface of which the metal of the blank is forced by the action of the rolls.

3. In diagonal-rolling machines, the combination, as herein shown and described, of a 75 conical mandrel with diagonally-acting conical rolls arranged on different sides of the path through which the blank travels, with their larger ends nearer together than their smaller ends.

REINHARD MANNESMANN.
